UNITED STATES PATENT OFFICE

CASSIUS C. SMILEY, OF INDIANAPOLIS, INDIANA.

EGG-CARTON.

1,112,859.

Specification of Letters Patent.

Patented Oct. 6, 1914.

Application filed October 20, 1913. Serial No. 736,220.

To all whom it may concern:

Be it known that I, Cassius C. SMILEY, a citizen of the United States, and a resident of the city of Indianapolis, county of Marion, and State of Indiana, have invented certain new and useful Improvements in Egg-Cartons, of which the following is a specification.

My invention relates to egg cartons and 10 more particularly to egg cartons which are collapsible.

The object of this improvement is to provide a simple and effective egg carton adapted to be folded substantially flat for 15 shipping and storage and one which is readily unfolded to operative condition.

Other objects will appear hereinafter.

The invention consists in the combinations and arrangements of parts hereinafter 20 described and claimed.

The invention will be best understood by reference to the accompanying drawing forming a part of this specification, and in which,

25 Figure 1 is a view in perspective of an egg carton erected in operative condition. Fig. 2 is a plan view of a blank used in the construction, Fig. 3, a similar view of another blank used in the construction, and 30 Fig. 4 is a view, in perspective, of the carton folded flat.

The preferred form of construction, as 35 illustrated in the drawing comprises a piece of heavy paper, cardboard or other suitable substance cut out, bent, notched and scored, forming the top 5, rear side 6, bottom 7 and front side 8 of the carton. The front side 8 is provided with projections 9 and is scored and folded on the lines 10 and ex- 40 tending substantially midway across the end of the carton then bent and scored on lines 11 and the rest of the projections disposed parallel with the front side 8 midway between the front and rear sides of the 45 carton. The two ends of the projections 9 are overlapped near the central portion of the carton. The projections 9 are also provided with notches 12 the purpose of which will be described later.

50 The rear side 6 is provided with projections 13 folded and scored on the lines 14. The projections 13 extend across the ends of the carton until they reach the projections 9 where they are bent and scored on lines 15. 55 At lines 15 the projections 13 are provided with slots 16 which engage corresponding

slots 12 of projections 9 locking the projections 13 to projections 9, as is clearly illustrated in Fig. 1. Formed on the ends of the lid 5 are projections 17 which are 60 scored and folded on lines 18 providing portions 19 which are adapted to extend over the ends of the carton. The portions 17 are then scored and folded on lines 20 with the extreme end portions of the projections 17 extending between the under edges of the ends of the carton and bottom 7 to lock the carton in operative condition. A plurality of partitions 21 are scored and 65 folded on lines 22 and the end portions outside of lines 22 are bent at substantially right angles and secured to the front side 8 and rear side 6, substantially as indicated in Fig. 1 by means of glue or other suitable adhesive. At the central portion of each of the partitions 21 is a slot 23 adapted to engage a corresponding slot 12 in projections 9. The partitions 21 with projections 9 70 form the inner partitions dividing the carton into separate egg compartments. 75

A carton made as indicated is easily folded by bending the partitions 21 and the ends of the carton on lines intermediate their ends thereby bringing the sides 6 and 8 against the folded partitions and ends. 80 This movement also folds bottom 7 longitudinally. Lid 5 is then folded over bottom 7 and sides 6 with projections 17 folded over the lid as indicated in Fig. 4, rendering the 85 carton in very compact condition for storage or shipment. The carton is erected to operative condition, as indicated in Fig. 1 by unfolding lid 5 and projection 17, then straightening partitions 21 and the ends of the carton. 90

95 While I have illustrated and described the preferred form of construction for carrying my invention into effect, this is capable of variation and modification without departing from the spirit of the invention. I, therefore, do not wish to be limited to the precise details of construction set forth, but desire to avail myself of such variations and modifications as come within the scope of the appended claims. 100

105 Having described my invention what I claim as new and desire to secure by Letters Patent is:

110 1. An egg carton comprising a flexible sheet cut out and forming the lid, bottom, front and rear sides of a carton; projections on said front and rear sides forming ends

- and certain egg compartment partitions; projections on the ends of said lid extending across said ends and between said bottom and lower edges of said ends; and partitions each formed of a separate sheet and extending laterally of the carton and having its ends secured to the front and rear sides of the carton, substantially as described.
- 10 2. An egg carton comprising a flexible sheet cut out and forming the lid, bottom, front and rear sides of the carton; projections on the ends of said front side, each projection having a portion forming a half 20 of one end of the carton and a portion extending parallel with said front side midway between said front and rear sides, the ends of said projections overlapping; projections on the ends of said rear sides, each 20 of said last mentioned projections forming
- the other half of one end of the carton and having its end portion engaging one of said first mentioned projections; lateral partitions each formed of a separate sheet and extending across said first mentioned projections having its ends secured to said front and rear sides, the intersecting points of said projections and partitions being provided with slits and interlocked; and extensions on the ends of said lid extending over 20 said ends and disposed between the lower edges of said ends and said bottom, substantially as described.

In testimony whereof I have signed my name to this specification in the presence of 35 two subscribing witnesses.

CASSIUS C. SMILEY.
